(57) **CLAIM**

The ornamental design for a display screen or portion thereof with transitional graphical user interface, as shown and described.

DESCRIPTION

FIG. 1 is a front view of a first embodiment of a display device or portion thereof with transitional graphical user interface showing a first image in a sequence, showing our new design;

FIG. 2 is a front view showing a second image thereof; FIG. 3 is a front view of a second embodiment of a display device or portion thereof with transitional graphical user interface showing a first image in a sequence, showing our new design;

FIG. 4 is a front view showing a second image thereof; FIG. 5 is a front view of a third embodiment of a display device or portion thereof with transitional graphical user interface showing a first image in a sequence, showing our new design;

FIG. 6 is a front view showing a second image thereof; FIG. 7 is a front view showing a third image thereof; FIG. 8 is a front view of a fourth embodiment of a display device or portion thereof with transitional graphical user interface showing a first image in a sequence, showing our new design;

FIG. 9 is a front view showing a second image thereof; FIG. 10 is a front view showing a third image thereof;

(Continued)

FIG. 11 is a front view of a fifth embodiment of a display device or portion thereof with transitional graphical user interface showing a first image in a sequence, showing our new design;

FIG. 12 is a front view showing a second image thereof; and, FIG. 13 is a front view showing a third image thereof. The appearance of the transitional graphical user interface sequentially transitions between the images shown in FIGS. 1-2, 3-4, 5-7, 8-10 or FIGS. 11-13.

The process or period in which one image transitions to another image forms no part of the claimed design. The outermost pair of broken lines showing a display screen or portion thereof remaining broken lines showing elements of the graphical user interface illustrate portions of the article that form no part of the claimed design.
